MOTOR BOARD

Frank R. Clark, Dallas, Tex.

Application December 29, 1949, Serial No. 6,909

Term of patent 14 years

(Cl. D71—1)

To all whom it may concern:

Be it known that I, Frank R. Clark, a citizen of the United States of America, residing at Dallas, in the county of Dallas and State of Texas, have invented a new, original, and ornamental Design for Motor Boards, of which the following is a specification, reference being had to the accompanying drawings, forming a part hereof.

Figure 1 is a perspective view of the motor board;

Figure 2 is a top plan view of the same;

Figure 3 is a front elevation of the motor board;

Figure 4 is a rear elevation of the motor board; and

Figure 5 is a side elevation of the same.

The characteristic features of my design reside in the parts shown by means of full lines in the drawing.

I claim:

The ornamental design for a motor board, substantially as shown and described.

FRANK R. CLARK.
